[57] CLAIM

The ornamental design for a device to increase foot traction, as shown and described.

DESCRIPTION

FIG. 1 is a top plan view of a device to increase foot traction showing my new design;

FIG. 2 is a front elevational view;

FIG. 3 is a bottom plan view; and,

FIG. 4 is a side elevational view showing the device in a position of use.

The broken line showing of a foot and shoe and the attaching means in FIG. 4 is for illustrative purposes only and forms no part of the claimed design.
